UNITED STATES PATENT OFFICE.

EMERSON L. CLARK, OF LAKEWOOD, OHIO, ASSIGNOR TO NATIONAL CARBON COMPANY,
OF CLEVELAND, OHIO, A CORPORATION OF NEW JERSEY.

COMPRESSION-RHEOSTAT.

1,143,810.

Specification of Letters Patent. Patented June 22, 1915.

Application filed May 31, 1912. Serial No. 700,558.

To all whom it may concern:

Be it known that I, EMERSON L. CLARK, a resident of Lakewood, in the county of Cuyahoga, in the State of Ohio, have invented new and useful Improvements in Compression-Rheostats, of which the following is a clear and exact description.

This invention relates to rheostats of the compression type in which the resistor elements consist of carbon, graphite or mixtures of these substances with other materials. However, the invention is not limited to the use of any specific materials, and hence may embrace resistors composed 15 of any materials.

One object of my invention is to construct a rheostat with readily replaceable resistor units each having means rigidly attached thereto for radiating the heat.

20 Another object is to construct a rheostat with slight frictional resistance to movement so that the elements when compressed or released from pressure will all move in unison.

Other objects will appear in the appended 25 description.

Referring to the figures, Figure 1 is an end view of a resistor element. Fig. 2 is a plan view of the element shown in Fig. 1. Fig. 3 is a plan view of the radiating plate 30 before the carbon or composition blocks are attached thereto. Fig. 4 is a sectional view of the radiating plate taken on the line A—A of Fig. 3. Fig. 5 is a sectional view 35 of the radiating plate taken on the line B—B of Fig. 3. Fig. 6 is a sectional view of the resistor element and radiating plate taken on the line C—C of Fig. 2. Fig. 7 is a sectional view of a modification showing 40 a resistor element having only one composition block. Fig. 8 is a plan view of another modification in which the composition blocks are arranged at one side of the radiating plate. Fig. 9 is an end view of another modification. Fig. 10 is a plan view 45 of the resistor element shown in Fig. 9. Fig. 11 is a sectional view of the resistor element taken on the line D—D of Fig. 10. Fig. 12 is a plan view of the radiating plate 50 shown in Figs. 9, 10 and 11. Fig. 13 is a modification similar to that shown in Figs. 9, 10, and 11 in which a guaze radiating plate is used. Fig. 14 is a sectional view 55 of the resistor element taken on the line E—E of Fig. 13. Fig. 15 is a modification in which the composition blocks are ce-

mented to the radiating plate. Fig. 16 is a modification arranged for radiating heat without the use of separate heat conducting plates. Fig. 17 is a plan view of one of the blocks shown in Fig. 16. Fig. 18 is an end view of a modification similar to Fig. 16. Fig. 18^a is a modified form of resistance block. Fig. 19 is a modification in which the radiating plate is cast in grooves in the composition blocks. Fig. 20 is an isometric view of the composition blocks of Fig. 19 before the plate is cast therein. Fig. 21 is an end view of the modification shown in Fig. 20 with the grooves arranged parallel. Fig. 22 is a modification showing a resistor consisting of one block with a radiating plate cast in grooves therein. Fig. 23 is a side elevation of a rheostat in which the resistor elements are used. Fig. 24 is a plan view of the rheostat shown in Fig. 23. Fig. 25 is an elevation of the end plates of the rheostat shown in Figs. 23 and 24. Fig. 26 is a modification of Figs. 23 and 24 in which the resistor element is suspended on parallel bars. Fig. 27 is a partial sectional view of the point of support of the screw rod against the end plate. Fig. 28 is a partial sectional view of another modification for communicating pressure. Fig. 29 is another modified form of block. Fig. 30 is a modified form 85 of rheostat. Fig. 31 is a section on F—F of Fig. 30.

Referring to Figs. 3, 4 and 5, lugs 1 are punched in a plate 3 so as to extend on one side thereof. These alternate with lugs 2 punched so as to extend on the other side of the plate. Composition blocks 4 are then placed between the lugs, one on each side of the plate. The lugs are then firmly pressed against or into the composition blocks as is 95 shown in Fig. 6. This arrangement provides for a very rigid resistor having a radiating plate in good contact with the sides of the composition blocks.

In order to prevent the metal from oxidizing and producing an undesirable resistance at the contact surface, the metal plate is coated with some metal that will not oxidize readily under the heat to which the element will be subjected in practice. The 100 plate is preferably coated with nickel, though copper or other metal may be used.

In Fig. 7 a modification is shown in which lugs are punched only on one side of the plate. The resistor element then consists of 105

only one block in connection with each radiating plate.

In Fig. 8 a modification is shown in which the composition block or blocks are placed 5 near one edge of the radiating plate. The advantage of this arrangement will be explained later.

In Figs. 9, 10, 11 and 12 a modification is shown in which the composition materials 10 are pressed into and through holes 5 in the radiating plate 3, as shown in Fig. 12. The holes punched in the radiating plate may be of various shapes and sizes and the arrangement of the holes may be varied as desired. 15 The plate and composition material properly mixed with a suitable binder are placed in a mold and put under hydraulic or other pressure which forces the material in intimate contact with the parts of the radiating plate 20 as is shown in Fig. 11.

In Fig. 13 the radiating plate 3 is displaced by the gauze plate 6. The material forming the block 4 is pressed around the wires in the gauze plate in the same manner 25 as has been described in modification in Figs. 10, 11 and 12. The cross section of this type of resistor element is shown in Fig. 14.

In Fig. 15 the composition blocks are 30 either brazed or cemented to the radiating plate 3. The brazing material or conducting cement is shown at 4', the thickness being exaggerated somewhat to make the construction clear. When the blocks are to be 35 brazed to the plate they are first coated on one side with copper or other metal and then the plating is joined to the plate by brazing in the usual manner. When the blocks are cemented to the plate they need not be copper 40 coated. Conducting cements are well known in the art, and as a typical example the following may be given: 100 parts graphite, 40 parts bronze powder and enough glucose or sugar and water to make a stiff paste. The 45 paste can be applied to either the plate or the resistor and the two parts pressed together in proper relation. They are then backed to a sufficient temperature to carbonize the glucose or sugar. After baking 50 it will be found that the cement is conductive and will firmly join the resistor to the plate. The shape of the blocks and plate in Fig. 15 is the same as is shown in prior figures with the exception that the plate has 55 no notched lugs.

In Fig. 16 an arrangement is shown whereby provision is made for getting rid of the heat without the use of metallic plates. The composition blocks 7 have corrugations 8 60 extending along the sides of the blocks as shown in Figs. 16, 17 and 18. These blocks are placed with the corrugations extending vertically so that there will be a circulation of air between the blocks. The heat is 65 readily dissipated by the circulation of air

through the corrugations. The corrugations would aid in dissipating the heat of the blocks if they were placed in the rheostat so that they would extend in a horizontal direction, but the circulation of air will be 70 much greater if the first described arrangement is followed. It is obvious that the grooves may be of various shapes. In Fig. 18 slightly different shaped grooves are 75 shown. In Fig. 18^a the grooved surfaces are placed in contact. The holes 8' are for the purpose of suspending the plates in a rheostat as described later.

In Figs. 19 and 20 the composition blocks 4 have undercut corrugations or grooves extending across one side. The blocks are placed in a proper mold with the grooved surfaces in contact or closely adjacent and with the grooves of the one block running approximately at right angles to those of the other, and molten metal is poured in so that it will entirely fill all the grooves in the plate and form a radiating plate 9 as shown in Fig. 19. The mold, of course, will be arranged in well known ways so that this plate 90 can be cast. It is obvious that the plates shown in Figs. 19 and 22 as well as those in the other figures, may be square, circular or any other shape. The blocks need not be necessarily arranged with the grooves at 95 right angles. They may be arranged at various angles or they may be parallel. Fig. 21 shows the latter arrangement. The preferable arrangement, however, is with the grooves approximately at right angles. The 100 material used for casting may be iron, copper, zinc, aluminum or any other metal or alloy. The material may be cast in the blocks by pressure casting well known in the art. 105

In Fig. 22 a resistor is shown consisting of only one block with undercut grooves and a radiating plate cast therewith.

Referring to Fig. 23, a rheostat is shown in which the resistor elements are used. 110 End plates 10, 11 are joined at the corners by four rods 12 properly fastened by the nuts 13. The shape of the plates and the arrangement of the holes is shown in Fig. 25. The holes 14 receive the rods 12. In 115 the center a plate 14', somewhat similar to plates 10 and 11, is fastened rigidly to the rods 12 by screws 15 or by other appropriate means. Insulated rods 16 pass loosely through holes 17 in the plates 10, 11 and 14 120 and are fastened at each end of the rheostat to bars 18 and 19. A screw 20, having an appropriate wheel 21 fastened thereto, is threaded through the bar 18 and passes loosely through the hole 22 in the plate 10. 125 The pin 23 is fastened to the bar 19 and extends loosely through a hole in the plate 11. The resistor elements can be readily inserted or removed so that a defective one can be replaced without trouble. 130

The type of resistor elements in Figs. 23 and 24 is similar to that shown in Fig. 8, in which the composition blocks are secured at or near the top of the radiating plate. The 5 blocks may be secured in any of the ways disclosed herein. Each resistor element is supported on the lower rods 12 by means of its radiating plate as shown in dotted lines in Fig. 25.

10 End plates 24, 25 are placed at each end of the rheostat. These plates must be rigid enough to transmit the pressure uniformly over the surface of the composition blocks when applied through the screw 20 and pin 23. The end plates are preferably larger than the resistor blocks so as to have additional surface for radiating heat as is shown in the figures. The end plates are supported by the lower rods 12 in the same 15 manner as are the resistor elements. The lower parts of the end plates and of the radiating plates of the resistor elements admit of conductors being clamped thereto and hence the elements may be arranged in parallel groups if desired. As shown in Fig. 23, the terminals 26 and 27 are clamped to the end plates 24 and 25 so that all of the elements are in series.

20 In order to prevent any of the elements from being short circuited the rods 12 and 25 may be covered with transite tubing or any other electrical insulating and heat insulating material as is shown in section at 28 in Fig. 26. It will be understood that insulating bushings and washers will be used where the rods are joined to the end plates 10 and 11, as is indicated in Figs. 23 and 25 by the parts shown in solid black. The 30 holes 22 in the end plates 10 and 11 should be properly insulated by bushings 29 as is shown in Fig. 25. The insulation suggested is only one of many ways in which the short circuit may be prevented. Anyone skilled in the art could provide for properly insulating the parts, and hence these need not be gone into in detail.

35 The screw 20 should press against the plate 26 through a point or ball contact as is shown in Fig. 27. If the screw presses 40 against a flat surface the rotative movement of the screw will cause the plate to reciprocate sidewise and produce undesirable fluctuations in the resistance of the rheostat.

45 In Fig. 28 another arrangement is shown whereby the end plate is not caused to move sidewise. Sockets are formed in the plate 24 and the screw 20 which contain a hardened ball 30. The ball may have a retainer to prevent it from dropping out of the screw 50. The terminals 26 and 27 are shown connected to the end plates 24 and 25 so that the current traverses the composition blocks 4, the radiating plates, and the metallic plate 14' in series. By rotating the wheel 21, the 55 screw 20 forces the resistor elements on the

left hand side of the rheostat against the plate 14'. The reaction transmitted through rods 16 presses the pin 23 against the plate 25 and compresses the resistor elements on the right hand side of the rheostat against the metal plate 14'. If the pile is compressed from one side only so that it would be, say $\frac{1}{2}$ inch shorter than it originally was, the first block on the moving end of the pile would move $\frac{1}{2}$ inch, and the succeeding 75 blocks would move progressively less distances. If the pile is compressed from both ends as in applicant's case the two outside blocks would move only $\frac{1}{4}$ inch and the succeeding ones progressively less. Hence to 80 obtain the same resistance the average distance of movement of the blocks in one type is twice that of the other. In order to obtain gradual and uniform variation of resistance the movement must be uniformly 85 transmitted through the entire pile. It is evident, therefore, that the changes of resistance should be obtained with as small movement of the blocks as possible. The arrangement shown in Figs. 23 and 24 provides for such reduced movement. 90

If the resistor elements are compressed only from one side it takes a certain amount of movement of the first resistor block before pressure is transmitted to the last block, and hence at the first movements of the compression screw the last blocks will furnish a high contact resistance so that very unsatisfactory results will be obtained when the pressure is first applied and when it is 95 about to be removed. The relatively short compression rheostat therefore gives better results than a long one. By providing pressure at both ends I am enabled to use a rheostat of twice the length and obtain equal 100 efficiency. 105

Since the resistor elements are supported on the rods 12 by means of radiating plates they pivot at the point of support and move about the pivotal point under compression and on release of pressure. This reduces the frictional resistance and hence the resistor elements move readily and provide for uniform variation of resistance. If the composition blocks were placed at the bottom 110 of the radiating plates or near the middle, the mechanical resistance caused by the plates sliding along the rods 12 would prevent the elements from moving readily, and the variations of resistance would be irregular, especially at the point of maximum resistance. Of course, when the blocks are placed at the top of the radiating plates there will still be some sliding of the plates along the rods 12 at the pivotal points, but the movement is reduced, and by making the plates of sufficient size the movement will be 115 negligible. 120

In Fig. 26 an arrangement is shown where the blocks are fastened to the base of the 125 130

radiating plate. The resistor element is then supported on the upper bearing rods 12 by means of lugs or ears 31 at the upper edge of the radiating plate. It is obvious 5 that this arrangement will allow of the resistor elements pivoting on the bearing rods in a similar manner to that previously described.

In Fig. 29 another form of resistance 10 block is shown. Holes 32' extend through the block to promote cooling by means of air currents. The blocks would be arranged in the rheostat with the holes vertical.

In Figs. 30 and 31 a modified form of 15 rheostat is shown. Insulation boards 32, made for instance of transit are fastened to the end plates 33, and extend on both sides of the resistance blocks. The blocks are thus inclosed on four sides and a chimney 20 effect is produced whereby a draft is caused, indicated by the arrows 34, when the blocks are heated by the current traversing them. The end plates 33 are shown extending below the sides 32 so that the rheostat can be 25 placed on a table or floor without impairing the circulation of the air. In this type the blocks of Figs. 16, 18 or 18^a are suspended by a wire 35 which extends through two holes 8' and engages hooks 36 supported in 30 notches 37 in the transit boards. This arrangement is very simple and on account of the flexibility of the wires the blocks move without any friction whatever. The remaining details of the rheostat are similar 35 to those in Figs. 23 and 24. The block shown in Fig. 29 may also be suspended in a rheostat in the same way by passing wires 35 through the holes 32'. The rheostat shown in Fig. 23 may be inclosed by boards 40 similarly to the arrangement shown in Fig. 31.

Having described my invention what I claim is:

1. In electric rheostats, a resistor element 45 consisting of a block of carbonaceous material and having channels for conducting a cooling fluid.
2. In electric rheostats, a resistor element 50 consisting of a block having grooves extending along the surface of one side.
3. A pile rheostat consisting of a series of carbon blocks having a plurality of channels for the circulation of cooling fluid.
4. In electric rheostats, a plurality of 55 double-faced resistor plates arranged in a pile, a plurality of corrugations in the faces of each plate whereby a plurality of channels are formed by the adjacent corrugations for conducting a cooling fluid.
- 60 5. A rheostat consisting of a series of blocks of carbonaceous material, an inclosure for the blocks having openings for

admitting and removing a cooling fluid whereby a circulation of said fluid is produced when the blocks become heated. 65

6. A rheostat having end plates, side plates coöperating therewith to form an inclosure and resistance blocks inclosed between the side plates whereby a chimney effect is produced when the plates become 70 heated.

7. In an electric rheostat, end plates, side pieces joining said end plates to form an inclosure, resistance blocks suspended between the side pieces and spaced therefrom to provide for the circulation of a cooling fluid. 75

8. In an electric rheostat, end members, side pieces joining said members, a block secured to the side pieces between the end members, resistors suspended between the 80 side pieces and means for compressing the resistors from both ends of the rheostat.

9. In a rheostat having end plates, side plates coöperating therewith to form an inclosure, a plurality of resistance blocks in 85 said inclosure, two flexible supporting means for each block, spaced apart and connected thereto, said means also being connected to the side plates and means extending through one of the end plates to apply pressure to 90 the resistance blocks.

10. In a rheostat having end plates, side plates coöperating therewith to form an inclosure, a stationary member intermediate to the end plates and coöperating with the side 95 plates to divide the inclosure into two compartments, a plurality of resistance blocks in each compartment, two flexible supporting means for each block, spaced apart and connected thereto, said means also being connected to the side plates, and means extending through each of the end plates to apply pressure to the resistance blocks in 100 each compartment.

11. A rheostat having resistance blocks, a support for said blocks and flexible, non-resilient means for pivotally suspending the blocks from the support, whereby said blocks can be freely moved. 105

12. A rheostat having resistance blocks 110 and flexible wires supporting said blocks whereby they may be freely moved.

13. In a rheostat a plurality of resistance blocks, supporting members, two flexible supporting means spaced apart and connected to each block and to the supporting members, and means for applying pressure to the blocks. 115

In testimony whereof I have hereunto signed my name.

EMERSON L. CLARK.
